UNITED STATES PATENT OFFICE.

JOHN AUDLEY GRANT, OF ATLANTA, GEORGIA.

AUTOMOBILE-TIRE.

1,391,541.

Specification of Letters Patent. Patented Sept. 20, 1921.

Application filed January 15, 1920. Serial No. 351,725.

To all whom it may concern:

Be it known that I, JOHN A. GRANT, a citizen of the United States, residing at Atlanta, in the county of Fulton, State of Georgia, have invented certain new and useful Improvements in Automobile-Tires, of which the following is a description, reference being had to the accompanying drawings and to the figures of reference marked 10 thereon.

This invention relates to pneumatic tires, and more particularly to that type in which the inner pneumatic tube is of smaller cross sectional area than the outer casing and is 15 supported therein and protected from puncture by an intervening filling of resilient material.

In prior devices of this kind, it has been customary to only partially surround the inner tube with this sustaining and protecting medium, that portion of the inner tube contiguous the lower side of the inner wall of the outer casing adjacent the bead being unsupported so as to provide air spaces between the inner tube and casing to relieve the sides of the latter of the usual side pressure of the inner tube against it in order to prevent blowouts from the side or rim of the casing, but such a construction is defective 25 because the inner tube tends to bulge out into these so-called air spaces and becomes pinched and worn, resulting in blowouts.

One of the objects of this invention is to overcome this defect by spacing the inner 35 tube from the casing at all points by means of a medium of yielding material completely surrounding the inner tube and occupying the space between it and the casing whereby the tube is resiliently supported and maintained in inflated position and is protected from puncture or rupture throughout its entire extent.

A further object consists in providing the pneumatic tube of this construction with an 45 interior filling of yielding material, which acting in combination with the air pressure of the tube and the outer yielding sustaining medium provides a tire combining maximum resiliency with durability.

Still another object of this invention resides in providing suitable casings for this filling medium and constructing the same whereby the tube may be readily assembled 50 within its protecting and sustaining envelop

and outer casing, and whereby the filling 55 medium is maintained in fixed position relative to the inner and outer elements of the tire.

These and other objects will in part be obvious and will in part be hereinafter more 60 fully disclosed.

Referring more particularly to the drawings:—

Figure 1 represents a cross sectional view 65 of the improved tire, and

Fig. 2 is a partial sectional side view of the same.

In general, this invention embraces an outer casing or shoe of the usual construction and an inner tube of substantially 70 smaller cross sectional area arranged within the casing adjacent the bead thereof and spaced entirely from the inner walls of the casing. This space is filled with a suitable sustaining medium such as cotton, which 75 provides an inclosing casing or envelop for the inner tube entirely surrounding the latter and bearing throughout its entire extent directly upon the inner and outer walls of the casing and inner tube respectively. 80 In addition to this construction, the inner tube is provided with a cotton filler which, acting co-jointly with the air pressure in the pneumatic tube, maintains the resiliency of the tire, and which, in the event of a puncture of this inner tube, provides a partial 85 sustaining and cushioning member for the collapsed tube.

Referring more particularly to the drawings, the tire consists of an outer casing 1 of 90 the usual type and an inner pneumatic tube 2 arranged adjacent the bead 3 of the casing and similar in all respects to an ordinary inner tube except that it is substantially 95 smaller in cross sectional area and is thicker, in the present instance, being from one to one and half inches in thickness. This tube is maintained in spaced relation to the inner walls of the casing by a filler or sustaining and protecting medium of elastic material 4, such as cotton or linters.

As shown in Fig. 1, this filler entirely encases the inner tube, providing at the bead portion of the casing a somewhat thin sustaining and protecting layer, which gradually increases in thickness in the direction of the casing tread where it provides a maximum protection. The inner tube and outer

casing are separated from the cotton by layers of canvas 5 and 6 which hold the cotton in fixed relation to the tube and casing.

In certain cases where it is desirable to provide for the removal of the inner tube, the canvas layers and cotton filling are slit as at 7 to provide an annular opening just opposite one of the beads of the casing, the ends of the slitted portions lying flush 10 against the inner wall of the bead when closed.

In addition to maintaining the inner tube inflated in the usual manner by air pressure, it is provided with a filling of cotton 8 which 15 not only serves to prevent the rapid escape of the air when the tube is punctured by sealing the opening but which also provides a resilient cushion or support to hold the shape of the tube when the same tends to 20 collapse when punctured.

By constructing a tire as above described, the inner tube is sustained in inflated position throughout its entire surface since the cotton envelop spaces it from the walls of 25 the casing and rim at all points, and there is no danger of puncture due to airspaces at the sides of the casing adjacent the beads nor is there any chance of the inner tube becoming pinched or rubbed.

The main thickness of the cotton filling 30 being adjacent the tread, the maximum protection is afforded at this point and due to the peculiar impenetrability of compressed

cotton a tire of this construction can be worn down to the very inner surface of the tread 35 without danger of puncture or blowouts.

It is obvious that minor changes in the details of construction may be made without departing from the spirit of the invention as set forth in the appended claim. 40

Having thus described the invention, what I claim as new and desire to secure by Letters-Patent, is:—

In a tire, the combination of an outer casing, a pneumatic inner tube of substantially 45 smaller cross sectional area than said casing arranged adjacent the bead thereof and in spaced relation to the inner walls of said casing, said inner tube having a sustaining filling of cotton, a removable envelop entirely inclosing said inner tube, said envelop including inner and outer canvas linings adapted to snugly fit the inner and outer circumferential walls of the tube and casing and provided with a sustaining and protecting 50 cotton filling to yieldably sustain the casing and to provide a protecting guard for the inner tube, said lining members and filling being provided with a circumferential slit for the removal of the inner tube, the 55 ends of said slit abutting between the inner tube and the wall of the bead to provide an unbroken surface therebetween.

In testimony whereof, I affix my signature.

JOHN AUDLEY GRANT.
